UNITED STATES PATENT OFFICE.

HORACE R. WILSON AND FRED D. WILSON, OF HARVEY, ILLINOIS.

ROAD GRADER.

Application filed September 22, 1926. Serial No. 137,143.

This invention relates particularly to that class of wheeled road graders provided with tiltable supporting and steering wheels and a diagonally disposed, laterally shiftable, 5 moldboard or blade, working in conjunction therewith for the general purpose of grading roads and making or cleaning out ditches at the side thereof.

In building a new road, recrowning an old 10 one, or cleaning the ditches at the side thereof, it is always necessary, with the type of grader to which we refer, for the material of which the road is made to be taken from the side and deposited in the approximate 15 center in order that proper drainage may result and this, of course, involves the movement of the material in a lateral direction relative to the travel of the machine.

This is accomplished, generally speaking, 20 by adjusting the moldboard to an angle, suitable to the particular condition, with one end in advance of the other, the material, as loosened, being moved along the face and allowed to discharge off the rear end, at the 25 same time being transferred toward the middle or crown of the road a distance in proportion to the angle and length of the blade and obviously the resistance and friction of 30 the material against the blade is also in proportion to the angle and length of same taken in connection with the amount and condition of the material.

This uncertain and sometimes relatively 35 great side thrust must, of course, be successfully resisted by the machine as a whole if a specified course is to be maintained and this is most successfully accomplished by leaning the rear supporting wheels toward the discharge end of the blade, thereby presenting a greater proportion of the tire 40 faces in the direction of the thrust, and it is well known to those informed that the leaning of these wheels must be, as near as possible, in proportion to the side thrust developed, as otherwise, should they be allowed 45 to remain in the maximum tilted position and, for instance, the blade slightly raised, or for any other reason, the side thrust be reduced the course of the wheels, together 50 with the delivery end of the blade, will be immediately changed in proportion to the thrust reduction and they will run toward the center of the road resulting in very uneven and unsatisfactory work.

In other words, the rear supporting wheels 55 tilted to a given angle to the left, take a course to the left of the forward untilted wheels, with the blade idle, and do not follow directly behind the forward wheels, and obviously, when the blade is lowered to an 60 operating position delivering to the left they will successfully resist only the amount of side thrust of material necessary to cause 65 their return to a position directly in line with the forward wheels and should the blade be pushed deeper into the road, and the side thrust on same thereby be increased, or withdrawn and the side thrust 70 reduced, the wheels must be tilted more and less, respectively, in order that a straight 75 and pleasing delivery may result. It is worthy of note that it is not always necessary to tilt all the wheels because of the fact 80 that where tractors are used to draw the machine the tractor is positioned near the center of the road and a connecting cable, of sufficient length to permit the grader to work in the ditch, counteracts, to a great extent, because of the angle of draft, the side thrust of the material at the front end 85 of the machine.

However, it is understood that when drawing the grader directly behind the tractor, as in smoothing the road crown, the grader is then unassisted by the draft cable and 85 must depend entirely upon its own devices for resisting this thrust.

From the foregoing it is to be understood 90 that all the wheels may be tiltable, relative to the vertical, but that it is not always necessary to operate all the wheels in a tilted position at one time or to even operate the front wheels at all under some conditions and that they may even be operated in opposite tilted positions at times because of the 95 variable conditions and loads to which a road grader is subjected but it is always desirable to operate the rear pair in a tilted position and the angle of tilt should be, as heretofore explained, just sufficient to counteract the before-mentioned side thrust, which obviously, must be easily changeable because of the very irregular nature of the work done, and when no work is being done by the blade even the rear wheels must be 100 quickly righted if serious damage to their bearings is to be avoided.

It should be remembered that the strain

on the wheel bearings is just as variable as the work at the blade and in fact continues even after the blade has been lifted to an inoperative position and the importance, 5 from this standpoint, of causing co-action between the movement of the blade and the movement of the wheels is great, inasmuch as when in operation the weight of the blade and associated parts is removed from these 10 bearings and placed on the ground and a serious thrust is changed from a downward to a lateral one very suddenly, and if the wheels are not properly tilted causes the early destruction of the ends of the wheel hubs.

15 We are acquainted with the fact that road grading machines equipped with tilttable wheels are old in the art and that the before-mentioned peculiarities of this type of machine are common knowledge to all those 20 associated with them as is borne out by the fact that all popular machines now on the market provide adjustment for shifting the blade and for tilting the wheels, these adjustments, to the best of our knowledge always being made independently and manually.

25 It therefore appears that the desirability and usefulness of the objects of this invention will be readily apparent when it is realized that the relative positions of the elements in question are now maintained by manual means and that it is a physical impossibility, to say nothing of the labor involved, to bring about a condition, as ideal 30 for the working parts of the machine, so nearly maintaining the maximum efficiency thereof, or accomplishing as desirable results, with reference to the quality of work done, as with our machine.

40 The main object of this invention is the construction of a road grading machine wherein the side thrust of the material against the blade sets in operation mechanism automatically resisting such thrust.

45 Another object of this invention is the provision of means tilting the carrying wheels on their axles in one direction when the blade is shifted in the opposite direction.

50 Another object is the construction of a blade shifting mechanism permitting both manual and automatic operation.

55 Still another object is the provision of means automatically straightening the rear wheels, when the blade is raised to an inoperative position.

60 One other object is the construction of a grader having tilttable wheels and means for automatically tilting them.

65 And yet another object is the construction of a grader provided with automatically tilttable wheels in combination with a blade shifting device adapted for actuation by both manual and power operated means.

66 With the above and various other objects

in view, the present invention consists in the combination and arrangement of parts hereinafter more fully described, illustrated in the accompanying drawings and more particularly pointed out in the appended 70 claims, it being understood that changes may be made in the form, size proportion, and even method of obtaining these objects, without departing from the spirit or sacrificing any of the advantages of the invention. 75

In the drawings:

Fig. 1 is a plan of a grader embodying our invention.

Fig. 2 is a side elevation of the rear portion of Fig. 1, taken on line A—A, with the rear wheel omitted.

Fig. 3 is a rear elevation of Fig. 1 clearly showing the method employed to lean the wheels, also showing the counter-balancing 85 springs which assist and control this function.

Fig. 4 is a plan in detail, clearly showing the wheel-tilting mechanism shown assembled in Fig. 1.

Fig. 5 is a right side elevation of the rear of Fig. 1.

Fig. 6 is a plan of Fig. 3 taken on line B—B with a portion of the axle bars broken away.

Fig. 7 is a plan of another method of applying our invention to a grader frame.

Fig. 8 is a rear, sectional elevation of Fig. 7, taken on line C—C with the blade shown in full.

The drawings show a conventional form of grading machine, forward supporting wheels 10 and rear wheels 12, a main frame 14, and blade, or moldboard as it is sometimes called, 16, operatively attached to and pulled by the frame by means of the circle 18, gooseneck bars 20, and casting 22, which is universally pivoted to the forward end of the frame in any conventional manner permitting both lateral and vertical swinging of the blade and floating parts associated therewith.

The forward end of the frame 14 is pivoted to, and carried on, the axle 24, and the rear end is shiftably supported on the bars 26 (clearly shown in Figures 2, 3 and 6) secured together by any suitable means, such as bolts 28, forming an axle, at the ends of which are provided holes 30 (see Fig. 6) in which are pivoted the trunnions 32, said trunnions being formed on either side of the spindle casting 34. Each of the spindle castings 34 has, in addition to the normally horizontal spindle upon which the wheel is mounted, an upwardly extending arm 36 on the end of which is pivotally secured the spacer bar 38 for the purpose of holding the arms 36 always in a parallel position.

Rotatively mounted on frame 14 are the lifting cranks 40 and 41, supported at their 130

forward ends by the bar 42 and at their rear ends by the posts 44 and 45 respectively (shown in Fig. 1).

Rigidly secured to the rear end of each 5 is the worm gear 46 meshing with the worm 48 secured to shaft 50, and on the inner ends of the shafts 50, are rigidly secured the lifting wheels 52.

Pivotedly secured to the crank ends of the 10 shafts 40 and 41 are lifting rods 54, the lower ends of which are connected, also pivotally, to crossbars 56, said bars being a rigid part of the gooseneck frame by virtue of the bolts 58 passing through the bars 20. It 15 will therefore be understood that manipulation of the hand wheels 52 will either lower or raise the blade by lowering or raising the gooseneck frame to which it is connected and that because of the pivotal attachment 20 of casting 22 to the frame 14 it is possible, by moving the wheels 52 separately to change the elevation of either end of the blade independent of the other.

Hinged, for vertical movement, to the rear 25 ends of the bars 20 is a yoke 60, slidably mounted on the socket member 62 (see Figures 1 and 2) to the rear end of which is universally pivoted the adjusting bracket 64 slidably mounted on the bar 66, said bar being securely fastened to the main frame 14 30 in any suitable manner.

Threaded in the adjusting bracket 64 is the rod 68, slidably and rotatively mounted in the frame as shown in Fig. 4 at 70 and 35 on one end of which is suitably mounted means to cause its rotation, as a pair of gears as shown at 72 and 73 carried in the bracket 74 and provided with a rotatable shaft 76, having a crank 78 or other suitable means of rotation. The shaft 76, however, is adapted to permit a limited amount 40 of lateral movement of the shaft 68 without the impairment of function.

Secured to the opposite end of the shaft 45 68 is a cylindrical shaped member 80 having formed in its periphery, in planes at right angles to its axis, splines 82 adapted to mesh with the gear segment 84 and cause its rotation around the pivot 86 when the 50 shaft 68 is moved endwise through the bearing 70. It is well here to note that while the splines, or ridges, on 80 function like the teeth on a common rack, when 68 is moved endwise, the shaft is freely rotatable 55 by the crank 76 at all times without interfering with the mesh of 80 and 84.

Attached to 84 on the opposite side of the pivot 86 is the arm 88 and pivotedly attached thereto is one end of the connecting rod 90, the opposite end of which is pivotally connected to the spacer bar 38.

Referring to Fig. 2, between the angle bars 26 is slidably mounted in the brackets 92 the shaft 94, having rigidly secured thereon the casting 96 with an upwardly extend-

ing ear 98 to which one end of the rod 100 is pivoted, the other end of this rod being pivotally attached to the spacer bar 38. Loosely mounted on the shaft 94 on either side of the casting 96 are the contractible 70 springs 102 the outer ends of each pressing against 92 which are secured to the axle bars 26 by any suitable means, as, for instance, with rivets.

It will be understood from the foregoing 75 that the blade 16 is movable vertically, at either end or both, by the manipulation of the hand wheels 52 and that by the rotation of the shaft 76 by means of the handle 78 the threaded shaft 68, by virtue of the internally threaded bracket 64 will when turned, cause 62, together with 60, to move in either direction across the frame carrying with it the rear ends of the bars 20, operatively attached to which is the blade 16. The blade 16 is mounted for rotation about the pivot 104 being retained in any selected position by the pin 106, being placed in one of the holes 108, the pin 106 being held in the proper relation to the bars by the bracket 90 110.

It will also be understood that any lateral movement of the blade, because of its connection through the bars 20, the yoke 60, the socket casting 62 and the bracket 64, will 95 cause a similar lateral movement, in fact a greater movement of the shaft 68 carrying with it the member 80 which by meshing with the segment 84, causes movement of the rod 90 in the opposite direction. The rod 90 being connected to the spacer bar 38 transfers this lateral movement causing the rotation of casting 34 about the pivot 32 and tilts the spindles.

Attached to the rear of one of the angle 105 bars 26 is a gear rack 112 in mesh with the pinion 114 secured on the shaft 116 having, upon its upper end, means for rotating it, as, for instance, the wheel 118. Slidable vertically, in the frame, but otherwise secured in any suitable manner, and adjacent the pinion 114, is a rod 120 having its lower end formed to engage the teeth in the pinion 114, to prevent its rotation and having attached to its upper end the foot-pad 122 110 beneath which is a contractible spring 124 resting upon the upper side of the platform 126. By first depressing the rod 120, causing its disengagement from the pinion 114 the rotation of the wheel 118 turns the pinion 114 which moves the rack 112 and therefore, the entire rear axle, in a lateral direction relative to the frame, it being understood that the connecting rod 90 is first disconnected from the spacer bar 38 and later adjusted to 120 any of the holes 128 (Fig. 1), suitable to the changed position.

It is readily apparent from the immediate foregoing disclosure that should it be desired to cause the wheels 12 to assume an ab- 130

normal angle relative to the vertical, as for instance in deep ditch work, the rod 90 may be moved to one of the holes (128) in the bar 38, producing the wheel inclination desired without effecting their co-action with the moldboard, when in operation. Neither do we desire to be limited to the exact method of adjustment shown for this purpose, as obviously any easily shiftable means may be used to connect the part 38 and 90, or, the member 90 itself may be telescopic and the purpose accomplished.

In controlling the lateral movement of a grader blade relative to the frame, it is generally conceded that there are two distinct points of attachment for the connecting mechanism, each having certain advantages over the other, for instance, if ease of operation is desired, the gooseneck members 20 are controlled from their extreme rear, but at this point much more movement is necessary to gain a specified lateral movement at the blade center 104, than is necessary when the control means is attached approximately 25 in line with the center of the blade circle 18. It should also be noted that any side strain on the blade caused by the movement of material will be much more severe in the latter case, but less movement required of the 30 mechanism (than in the former case) to move the blade the same distance and we have therefore, in Figures 7 and 8, shown a form of our invention adapted to a grader of the latter class with the knowledge that in certain sizes a greater thrust is necessary 35 to lean the wheels than is practical with the former type.

In graders of the latter type it is common practice to attach to the frame a laterally movable bar, similar to 130 (Figures 7 and 40 8) having riveted to its side the rack 132 actuated by a worm 134, which in turn is rotated by the gears 136 and 137, the shaft 138 and hand wheel 140, it being understood 45 that the worm 134 has always, heretofore, been held against lateral movement by suitable bearings.

In applying our invention to this common mechanism we secure the worm 134 to the 50 shaft 142 which is adapted to move endwise in either direction when required to the limit of the springs 144 loosely mounted thereon, each having an end against the worm hub 134 and an end against a suitable 55 stationary member attached to the frame, such as the shaft boxes 146 in which the shaft may slide laterally and rotate.

This arrangement, it will be noted, permits the worm 134 to be actuated in the usual 60 manner by the hand wheel 140, yet because of the presence of the springs 144, any severe lateral thrust against the blade causes lateral movement of the rack and worm through the medium of the rod 148, as shown 65 in Fig. 8, the springs 144 tending to return

the worm and shaft to a central position when said side thrust is removed from the blade.

Swiveled to an end of the shaft 142 is one end of the lever 150, fulcrumed at 152 to 70 the frame 14, the other end of the lever pivoted at 154 to the rod 156 which rod is pivoted at its opposite end, to the spacer bar 38, thus connecting the shifting mechanism with the wheels 12 through the medium of 75 the spindle casting 34. 160 (in Fig. 8) represents a crossbar secured to the rear side of the bent ends of the gooseneck bars 20^A, also serving in this type of grader as a supporting means for the center 104.

From the foregoing description of both adaptations of our invention it will be seen that instead of rigidly retaining the blade in any selected lateral position, as is usual with common graders, our blade is allowed 85 to shift, to a limited extent, by the force of the material acting against its face in the direction of the arrows 162, Fig. 1, and as this force is the result of the draft of the tractor or other propelling means it follows 90 that in this sense, our blade is shiftable by power derived from the draft of the tractor through the connecting cable and also automatic in its action, inasmuch as the heavier the load the more it shifts (within certain 95 limits) and vice versa, without the attention of the operator, and that also in both cases the springs 102 and 144 automatically tend to return, to their normal positions, both the 100 blade and wheels.

For the reasons and in the sense stated above, we are claiming wheels automatically 105 tilttable by power means. It is of course apparent that in so far as the lateral hand adjustment is concerned our machine has all 110 the capabilities found in either type and understood, too, that a portion of the shifting means, as for instance, 64 and 68, are shiftable by power in any position selected 115 by the actuation of the hand operated means 76 and 78 and it is with these facts in mind that certain of the following claims are drawn to claim, "shifting means adapted to be actuated by both power and hand operated means."

While we have shown and described in 120 considerable detail two specific embodiments of our invention, we are aware that there may be other ways of accomplishing the result, we claim, but it is to be understood that we do not limit ourselves to the details of construction shown, except in so far as we have included such limitations within the terms of the following claims in which it is 125 our intention to claim all novelty inherent in it as broadly as is possible in view of the prior art.

What we claim as new and desire to secure by Letters Patent is:

1. A road grader in combination, a main 130

frame and a moldboard, tilttable wheels supporting said frame and moldboard, and means tilting the wheels simultaneously with the shifting of said moldboard, for the purpose set forth.

2. A road grader, in combination, a moldboard, a main frame supporting the moldboard, tilttable carrying wheels supporting the main frame and means operatively connecting the moldboard and wheels causing simultaneous co-action thereof.

3. A road grader in combination, a main frame, a laterally shifttable moldboard beneath the frame and carried thereby, a tilttable carrying wheel supporting the frame and means, operatively connecting the moldboard and said wheel, adapted to cause simultaneous movement thereof, for the purpose set forth.

20 4. A road grader in combination, a main frame, supporting wheels therefor, a rotatable and laterally shifttable moldboard beneath the frame, and carried thereby and means, operatively connecting the moldboard and some of said wheels, whereby lateral movement of said moldboard causes a tilting of supporting wheels.

30 5. A road grader in combination, a main frame, supporting wheels therefor, a diagonally disposed, laterally shifttable moldboard beneath the frame and carried thereby and means operatively connecting the moldboard with some of said wheels whereby lateral movement of the moldboard in one direction causes a tilting of the supporting wheels in the opposite direction, for the purpose set forth.

40 6. A road grader, in combination, a main frame and a road engaging element, adapted for the lateral movement of material, and connected to the frame and supported thereby, means controlling the lateral movement of said element, and connected to the supporting wheels in a manner causing the automatic tilting thereof when said element is moved laterally.

45 7. A road grader, in combination a main frame, a moldboard, connected to and supported by said frame, and adapted to move material laterally, tilttable wheels supporting the frame, means attached to the frame, controlling the positions both of the moldboard with reference to the machine center and of the wheels with reference to a vertical plane, said means co-operating to cause a reverse movement of one relative to the other.

50 8. A road grader, in combination, a main frame mounted on tilttable supporting wheels, an earth moving element, engaging the road surface, adapted for the lateral movement of material beneath the frame, and automatically acting mechanism connecting said element with some of the wheels to resist the thrust caused by the lateral movement

of material against said element, for the purpose set forth.

9. In combination, a road grader comprising a diagonally disposed, laterally shifttable blade, tilttable wheels supporting and controlling said blade, and devices, secured to interposed frame work, adapted to permit both manual and automatic shifting of the blade for the purpose set forth.

10. In combination, a road grader comprising a laterally shifttable moldboard adapted to automatically shift its position in proportion to the side thrust thereon, spring devices adapted to resist said shifting and tilttable wheels supporting the moldboard and controlled by said spring devices for the purpose set forth.

11. In combination, a road grader comprising a main frame, a moldboard and tilttable supporting wheels and spring devices interposed between some of said wheels and the main frame to resist the tilting thereof, substantially as shown and for the purpose set forth.

12. In combination, a road grader comprising a main frame, a moldboard, automatically shifttable in a lateral direction, tilttable supporting wheels and spring cushion devices adapted to resist and control the shifting of said moldboard, substantially as shown.

13. In combination, a road grader comprising a main frame, a ground engaging element adapted to be moved laterally a predetermined distance when in an operative position, a tilttable pair of wheels in the rear of said element, means for simultaneously tilting said wheels with the lateral movement of said element and automatically acting means returning the wheels to a vertical position when the said element is in an inoperative position, for the purpose set forth.

14. In combination, a road grader comprising a main frame, a ground engaging element adapted to be moved laterally a predetermined distance, when in an operative position, by power derived from the draft means, a tilttable pair of wheels in the rear of said element, means for simultaneously tilting said wheels with the lateral movement of said element and automatically acting means returning the wheels to a vertical position when the said element is in an inoperative position for the purpose set forth.

15. In combination, a road grader comprising a main frame, supporting wheels, a moldboard and moldboard lateral adjustment means, a portion of said means adapted to be actuated by pressure against the moldboard and also by hand operated means, substantially as shown.

16. In combination a road grader comprising a main frame, supporting wheels therefor, a laterally shifttable moldboard,

moldboard shifting means, shiftable a pre-determined distance relative to the main frame and mechanism operatively connecting the shifting means with some of the supporting wheels for the purpose set forth.

17. In combination, a road grader comprising a main frame, a pair of forward supporting wheels and a pair of rear supporting wheels, a laterally shiftable moldboard, a shifting member controlling the moldboard laterally, said member adapted to be actuated by both pressure against the moldboard and hand operated means, independent of each other, and mechanism operatively connecting said shifting member with the rear supporting wheels substantially as shown and described.

18. In a road grader in combination, a main frame, a moldboard vertically and laterally movable relative to and carried by said frame, front and rear wheels supporting the frame and shiftable moldboard shifting means, in the rear of the moldboard, adapted to be actuated by the side thrust on said moldboard and also by hand operated means, for the purpose set forth.

19. In a road grader, in combination a main frame, a moldboard vertically and laterally movable relative to the frame, front and rear supporting wheels, some of which are tiltable, and shiftable moldboard adjusting means adapted to be actuated by hand means, when the blade is in one position, and by pressure against the moldboard when it is in another position said means being operatively connected to tilt one of the supporting wheels for the purpose set forth.

20. In a road grader, in combination, a main frame, and a laterally shiftable moldboard, an axle supporting the frame, supporting wheel spindles, provided with upwardly extending arms, pivoted to the ends of the axle, wheels rotatively mounted on the spindles, a bar connecting the free ends of the arms and mechanism adapted to automatically move said bar, laterally in one direction, without attention from the operator, for the purpose set forth.

21. In a road grader in combination, tiltable supporting wheels, a main frame, a material moving, ground engaging element, and pressure actuated means for tilting said wheels, said means connecting said element and wheels in a manner causing simulta-

neous coaction, substantially as shown and 55 described.

22. In a road grader, in combination, a frame, wheels supporting the frame, a moldboard carried by the frame and adapted to be shifted laterally, and cushion means 60 resisting the lateral shifting of said moldboard.

23. A road grader in combination, a moldboard, a main frame supporting the moldboard, tiltable carrying wheels supporting 65 the main frame, and mechanism operatively connecting the moldboard and wheels causing simultaneous co-action thereof; said mechanism adapted to be manually adjusted to change the relative position of the moldboard and wheels.

24. In combination, a road grader comprising an earth moving element, tiltable ground engaging wheels resisting said element, and devices operatively connecting 75 said wheels and element, adapted to permit both manual and automatic tilting of said wheels.

25. In a road grader in combination a frame, constantly parallel tiltable wheels supporting the frame, an earth moving element working in conjunction with the frame, and cushion means to assist and stabilize the wheel tilting operation.

26. In a road grader in combination, a frame, an earth moving element working in conjunction with the frame, constantly parallel, vertically tiltable wheels, supporting the frame and element, mechanism for tilting the wheels and cushion means in the wheel tilting mechanism adapted to stabilize the tilting thereof and assist in returning them to an upright position.

27. In a road grader in combination, a frame, an axle, constantly parallel tiltable wheels supporting the frame and axle, an earth moving element working in conjunction with the frame, and cushion means to assist and stabilize the wheel tilting operation, said cushion means being partly comprised of a coiled spring one end of which is held against an abutment normally stationary with said axle and the other end of which is held against an abutment movable 100 when the wheels are tilted.
